FIG. 1

FIG. 2

Figure 1 is a plan view of a linoleum surface covering or similar article showing a full width of the linoleum between the vertical edges and a vertically repeating unit between the horizontal dashed lines.

Figure 2 is an enlarged view of a portion of a repeating unit of the linoleum surface covering or similar article shown in Figure 1.

The characteristic feature of my design resides in the presence of multi-armed star-like decorative elements of three different sizes arranged in the manner shown upon a marbleized background to form a repeating unit as shown.

I claim:
